UNITED STATES PATENT OFFICE.

WILLIAM V. LOVELL, OF WILKINSBURG, PENNSYLVANIA, ASSIGNOR TO WESTINGHOUSE ELECTRIC & MANUFACTURING COMPANY, A CORPORATION OF PENNSYLVANIA.

HIGH-VACUUM PUMPING SYSTEM.

1,346,408.

Specification of Letters Patent. Patented July 13, 1920.

Application filed May 26, 1917. Serial No. 171,218.

To all whom it may concern:

Be it known that I, WILLIAM V. LOVELL, a citizen of the United States, and a resident of Wilkinsburg, in the county of Allegheny and State of Pennsylvania, have invented a new and useful Improvement in High-Vacuum Pumping Systems, of which the following is a specification.

My invention relates to pumping systems particularly adapted for the production of high vacua, and it has for its object to provide a system of the character designated that shall be compact in construction and efficient, inexpensive and effective in operation.

More specifically, my invention relates to that class of apparatus known as vapor or diffusion pumps, and it has for its object to provide apparatus whereby the condensate from the diffusion pump may be employed in a Sprengel pump or fall-tube to produce the preliminary or roughing vacuum.

The single figure of the accompanying drawing is a side view, partially in section and partially in elevation, of a pumping system embodying a preferred form of my invention.

In the production of extremely high vacua, such, for example, as are employed in vapor converters for the rectification of alternating current, the apparatus known as the diffusion pump has recently attained considerable prominence. Such apparatus has been disclosed and discussed in a number of technical articles, as, for example, in a paper entitled "A high vacuum mercury vapor pump of extreme speed" presented by Langmuir before the American Physical Society in April 1916, said paper being noted on page 49 of the "Physical Review" for July 1916. In its essence, said apparatus comprises means for producing a blast of substantially pure vapor such, for example, as mercury, said blast being delivered in such relation to the mouth of the exhaust tube that the gas in the container is entrained thereby and swept away, having its pressure radically increased. The exact method of operation is still somewhat in dispute but, apparently, there is some mechanical entraining, the apparatus working as does the ordinary injector and, apparently, there is also a tendency for the gas to be pumped to diffuse through the

material of the vapor blast, thus giving 55 rise to the term "diffusion pump."

The apparatus thus described is well adapted for raising the pressure of a gas from the extremely low pressures desired in vapor converters to the pressures which are 60 attainable by ordinary mechanical pumps but it is incapable of pumping to atmospheric pressure and it must, therefore, be operated in tandem with an ordinary mechanical pump which receives the gas at the 65 final pressure of the diffusion pump and raises it to atmospheric pressure. "Backing" or "roughing" pumps of this type are expensive and entail additional care and trouble in their maintenance. 70

By my invention, I may do away entirely with the necessity for using a distinctly operating roughing pump, diverting the condensate from the diffusion pump into a fall-tube and there causing it to act upon 75 the relatively high-pressure gas given off by the diffusion pump, raising said gas to atmospheric pressure and permitting its escape, or I may employ a simpler and cheaper roughing pump than is demanded by the 80 usual system.

Thus, it will be noted that I employ a pumping substance such, for example, as mercury, in two distinct stages. In the first place, said substance is used in the 85 form of vapor to produce an initial compression and is then used in the form of liquid to produce still further compression.

Referring to the drawing for a more detailed understanding of my invention, I 90 show a diffusion pump at 1, said pump comprising a boiler 2 provided with heating means 3 and discharging through a nozzle 4 into a closed container 5. The nozzle 4 is preferably surrounded by heat-insulating 95 material 6 so as to maintain a relatively high temperature in the incoming vapor blast, and the upper portion of the chamber 5 is preferably provided with a cooling jacket 7 to condense the vapor blast when it reaches the upper portion of said chamber. The container 8 to be exhausted is connected to the pump 1 by a tube 9, said tube discharging into the chamber 5 adjacent to the mouth of the nozzle 4. A tube 10 projects from the upper portion of the chamber 5 and extends downwardly a sufficient distance to produce a barometric vacu- 105

um, its lower end terminating beneath a pool of liquid 11. The upper end of the nozzle 4 is some distance above the floor of the chamber 5 and the condensate from the 5 upper portion of said chamber is thereby collected to form a pool 12. The level of the upper surface of the pool 12 is determined by a drainage tube 13 that discharges into the fall-tube 10. A return tube 14, 10 which may be closed by a valve 15, connects the pool 11 to the boiler 2, thus permitting a continuous circulation of the pumping medium.

Having thus described the structure of a 15 pumping system embodying my invention, the operation thereof is as follows. The valve 15 is closed to retain liquid in the boiler 2. Said liquid is brought to the boiling point by the heating means 3 to cause 20 a blast of vapor to issue from the nozzle 4 and sweep by the mouth of the tube 9. Gas, drawn from the container 8, is mechanically entrained thereby and diffused therethrough and is swept to the upper portion of the 25 chamber 5. At this point, the vapor issuing from the nozzle 4 is condensed and drips back into the pool 12, leaving the entrained gas free to pass into the tube 10. The result of this action is to produce a somewhat 30 higher gas pressure in the upper portion of the chamber 5 and in the tube 10 than exists in the container 8 and in the tube 9. The continued condensation of the vapor blast causes the overflow of the pool 12 into the 35 tube 13 whereby successive globules of liquid descend in the tube 10, carrying with them compressed gas drawn from the upper portion of the container 5, as in the ordinary Sprengel pump. The gas is released in 40 the pool 11 and escapes to the atmosphere and, as soon as a partial vacuum is formed, the valve 15 may be opened to permit the condensate to be sucked up through the tube 14 to again participate in the pumping 45 cycle.

The system which I have described to this point is operative to produce extremely high degrees of vacuum but is rather slow in its action, as the Sprengel pump is necessarily of low capacity, if operated by the condensate from the diffusion pump. It is sometimes advisable, therefore, where rapid pumping is required, to employ a mechanical pump, as shown at 16, said pump being connected to the fall-tube 10 through a valve 17. In operation, the "roughing" pump 16 may be operated to produce a partial vacuum in the chamber 5, rapidly producing the degree of vacuum where the 50 Sprengel and diffusion pumps may come into action most effectually, the pump 16, however, being far simpler and cheaper than would be permissible if said pump were operated directly in tandem with the diffusion pump alone.

While I have shown my invention in its preferred form, it will be obvious to those skilled in the art that it is susceptible of various minor changes and modifications without departing from the spirit thereof 70 and I desire, therefore, that only such limitations shall be placed thereupon as are imposed by the prior art or as are specifically set forth in the appended claims.

I claim as my invention:

1. The combination with a diffusion pump, of a Sprengel pump in series therewith and means whereby the latter is operated by the condensate of said diffusion pump.

2. The combination with a mercury diffusion pump, of a Sprengel roughing pump in series therewith, and means whereby said roughing pump is operated by the mercury condensed in said diffusion pump.

3. In a pump, the combination with a fluid boiler, of a closed container provided with heat-dissipating means, a nozzle connected to said boiler and arranged to project a vapor blast into said container, an 90 inlet port in the wall of said container adjacent to said nozzle, an outlet port in the wall of said container opposite said nozzle, a fall tube connected to said outlet port and terminating beneath the surface of a liquid 95 pool, and a drainage tube from the lower portion of said container to said fall-tube, whereby gas, entering at said inlet port, is entrained and diffused in said vapor blast, swept onward and compressed thereby at 100 said outlet port and withdrawn therethrough by the action of condensate entering said fall tube through said drainage tube.

4. The combination with a diffusion 105 pump, of a fall-tube, a connection from the outlet port of said diffusion pump to said fall-tube, and a drainage tube from the condensate pool of said diffusion pump to said fall-tube, whereby the action of the pump 110 condensate is to withdraw gas from said diffusion pump.

5. The combination with a diffusion pump, of a fall-tube, a connection from the outlet port of said diffusion pump to said 115 fall-tube, a drainage tube from the condensate pool of said diffusion pump to said fall-tube, said fall-tube terminating beneath the surface of a liquid pool, and a return tube from said pool to said boiler, whereby 120 the material of said pool is caused to circulate through said boiler, the vapor blast, and said fall-tube.

6. The method of employing a substance in pumping a highly rarified gas which 125 comprises vaporizing said substance, compressing said gas by a blast of said vapor, condensing said vapor, and further compressing said gas by the fall of the resultant condensate.

7. The method of employing a substance in the compression of a gas which comprises first acting upon said gas by a vapor blast of said substance to produce initial compression thereof, converting said substance into liquid form and then further acting upon said gas therewith.

8. A pumping device for raising the pressure of a gas which comprises a body of liquid, means for vaporizing said liquid, means for producing a blast of the resultant vapor in such relation to said gas as to continuously entrain and compress the same, means for condensing said vapor, and means

whereby the resultant condensate is caused 15 to move so as to again entrain and still further compress said gas.

9. A pumping system comprising a diffusion pump, a Sprengel pump, and a mechanical pump connected between said other 20 two pumps, and means whereby said Sprengel pump is operated by the condensate from said diffusion pump.

In testimony whereof, I have hereunto subscribed my name this 11th day of May, 25 1917.

WILLIAM V. LOVELL.
